SOLE

Filed April 19, 1922

Inventor:
Charles B. Spalsbury
By James R. Hodder
Atty.

UNITED STATES PATENT OFFICE.

CHARLES B. SPALSBURY, OF ST. LOUIS, MISSOURI, ASSIGNOR TO JOHNSON, STEPHENS & SHINKLE SHOE COMPANY, OF ST. LOUIS, MISSOURI, A CORPORATION OF MISSOURI.

SOLE.

Application filed April 19, 1922. Serial No. 555,587.

My present invention is a novel and improved form of sole; or a combined insole and outsole for use in manufacturing shoes, particularly intended for use in making my improved and novel form of shoe, by the method or process disclosed in my copending application Ser. No. 555,588, filed April 19, 1922. In carrying out the said process, it is important to provide an insole and outsole member, so formed and constructed; or so united when two separate layers or sole members are employed, that the upper materials may be lasted upon the insole member entirely around the edge, and then through and through stitching employed, engaging the marginal portions of both insole and outsole members, and the upper therebetween, in the well-known manner of McKay stitching.

In order to effect such a lasting action, particularly on the edge portions of the upper at each side of the forepart, I have devised a special lasting machine shown in my copending application Ser. No. 630,131, filed April 5, 1923, although any lasting instrumentalities may be used for the purpose and the shoe may be so made by hand.

In my present application I have elected to describe and claim the sole or combined insole and outsole members, either for making my improved shoe, or in the manufacture of the well-known and established type of McKay shoe. I am advised that the cutting of a sole into insole and outsole members, wherein the line of cut is at different levels or positions in the forepart and in the shank part, is new, and also it is new, so far as I am aware, to unite an ordinary insole and outsole intended for use in making McKay shoes, prior to the lasting, irrespective of the relative thicknesses and as both these kinds of sole constructions are capable of use advantageously in my improved shoe, by the process described in my said prior application, Ser. No. 555,588, filed April 19, 1922, I wish to claim the same herein broadly.

Referring to the drawings, illustrating a preferred embodiment of the invention:

Fig. 1 is a plan view of my novel form of sole constituting an insole and outsole member, cut or split from a single thickness, and also this figure illustrates two separate soles united at the forepart, to form a single

sole member preparing the same for lasting;

Fig. 2 is a side view of the sole as incorporated in the shoe;

Fig. 3 is a cross-sectional view on the line 3—3 of Fig. 1;

Fig. 4 is a cross-sectional view on the line 4—4 of Fig. 1, wherein the insole and outsole members are split from a single thickness of leather; and

Fig. 5 is a cross-sectional view on the line 4—4 of Fig. 1, illustrating a modified construction wherein separate insole and outsole layers are united.

As herein illustrated and as explained in said prior process application, I prepare a special sole for the purpose of making my improved shoe by my new process. Such a sole will first be described as made from a single layer or piece of leather. This sole leather is died out to suitable form and contour, as is customary. It is then split inwardly from the heel to approximately the forepart, preferably on a line of cleavage which will leave the greatest thickness for the insole member. The sole is then split inwardly from the toe portion and around the sides, on a line which will leave the greatest thickness on the outsole member. With the sole thus formed, the outsole member 1 and insole member 2 are separate at the heel and shank at toe and around the side portions, being united only at the central part of the forepart or ligature 3.

The insole member 2 is reduced in dimensions by being trimmed, formed or cut of appropriately less area and contour than the outsole. As illustrated in Fig. 2 the shoe upper 5 is lasted as shown between the insole and outsole members and the shank stiffener 6 also preferably positioned therebetween.

When it is desired to make this type of combined or double insole and outsole, with two separately formed layers or two soles 1 and 2, the insole member 2 would be first trimmed around or reduced in size appropriately to cooperate with the outsole 1 and then two members are applied together and united by lines of stitching 10 and 11, at the forepart, leaving a substantial marginal area at each side between the insole and outsole members to permit the lasting of the upper 5 at these points. I contem-

plate the use of the insole for ordinary McKay shoe manufacture, although I may use either form of insole in manufacturing an improved shoe by the novel process of my said prior and copending application. Where the sole is made of a plurality of separate and distinct members the two sole members may be of equal thickness throughout or may be of proportionately varying thickness to correspond substantially with the different lines of splitting or cut as shown in Fig. 2.

In either form I provide a combined insole and outsole member, preparatory to incorporating the same in a shoe by lasting the upper between the two joined or split portions, and completing the shoe by through and through or McKay stitching. This feature of making a McKay shoe by first uniting the insole and outsole members, I claim as new, and also the formation of an

insole from a single layer or sheet of material wherein the insole and outsole members are so split or cut as to provide a greater thickness of the outsole at the forepart and of the insole at the shank and heel part.

My present invention is further described and defined in the form of claim as follows:—

A combined insole and outsole member for McKay shoes, comprising a sole having an insole member and an outsole member so split or cut as to have the forepart of the outsole member of substantially greater thickness than the rear part, said members being united at the forepart only and adapted for having an upper lasted directly to the insole member without turning.

In testimony whereof, I have signed my name to this specification.

CHAS. B. SPALSBURY.
